CLAIM

The ornamental design for a multi-compartmented container with a hingedly attached lid, as shown and described.

DESCRIPTION

FIG. 1 is a top view of a multi-compartmented container with a hingedly attached lid showing my new design;

FIG. 2 is a front elevational view thereof;

FIG. 3 is a bottom view thereof;

FIG. 4 is a right side elevational view with the left side being a mirror image of FIG. 4;

FIG. 5 is a cross-sectional view taken along line 5—5 of FIG. 2;

FIG. 6 is a cross-sectional view taken along line 6—6 of FIG. 2; and,

FIG. 7 is a rear elevational view thereof.
